Fig 2

A PLOW WITHOUT A SPRING

J. D. WILLIOUGHBY'S design for Plow Springs

Des. 971

James D. Willoughby of Pleasant Hall Pa.
Letters Patent No 971. Date Oct 22 1857.

The schedule referred to in these Letters Patent and making part of the same.

To all whom it may concern:

Be it known that I James D. Willoughby of Pleasant Hall, in the county of Franklin and State of Pennsylvania have produced a new and original design which is to be stamped, painted, mounted, or in any manner affixed on vulcanised India rubber, to be used for spring clevises for plows, and I do hereby declare that the annexed description and drawing fully represent my design.

My design is shown and marked Fig 2 in the annexed drawing.

The design consists of a man, a horse and a plow - the plow being of ordinary construction and without my spring clevis attached to it. - the plow it will be seen is striking a stump or firm obstruction, the horse being thrown back upon his hamipes and injured by the concussion while the man being struck by the handles of the plow in the stomach or any other vulnerable part, is about to measure his length upon the ground.

The object of this design is to show the advantages of my spring clevis when used in plowing in bad land - saving the life of the man, the health of the horse, and the expense of a new plow, whenever the point of the plow strikes a stump or any firm

obstruction.

What I claim as my production and desire to secure by Letters Patent is the design herein represented, to be stamped, painted,..... moulded or in any manner affixed on Vulcanised India Rubber or its substitute, when used for the junction of spring clevises for plows or any other similar purpose.
